Specification for Design.

Patented Jan. 16, 1917.

Application filed September 13, 1916. Serial No. 119,982. Term of patent 14 years.

To all whom it may concern:

Be it known that I, BENJAMIN O. FANSLOW, a citizen of the United States, residing in Rye, county of Westchester, and State of New York, have invented a new and original ornamental Design for a Frame for Check-Protecting Machines, of which the following is a specification, reference being had to the accompanying drawing, forming part thereof.

Figure 1 is a front elevation showing the characteristic features of my frame for check protecting machines; and Fig. 2 is an end elevation of the frame shown in Fig. 1.

I claim:

The ornamental design for a frame for check protecting machines, as shown.

BENJAMIN O. FANSLOW.
